UNITED STATES PATENT OFFICE

90,861

DESIGN FOR A NECKPIECE FOR A WOMAN'S GARMENT OR SIMILAR ARTICLE

Martin Seidel, Bogota, N. J.

Application August 31, 1933. Serial No. 49,170

Term of patent 3½ years

To all whom it may concern:

Be it known that I, MARTIN SEIDEL, a citizen of the United States, residing in the city of Bogota, county of Bergen and State of New Jersey, have invented a new, original, and ornamental Design for a Neckpiece for a Woman's Garment or Similar Article, of which the following is a specification, reference being had to the accompanying drawing, forming part thereof.

being understood that the ornamentation of the portion appearing within the dotted lines is identical with that of the part shown in full.

I claim:

The ornamental design for a neckpiece for a woman's garment or similar article substantially as shown, and described.

MARTIN SEIDEL.
